UNITED STATES PATENT OFFICE.

HENRY POPE, OF CHICAGO, ILLINOIS.

REUSABLE KNITTED GAUZE SURGICAL DRESSING.

1,285,366.

Specification of Letters Patent. Patented Nov. 19, 1918.

Application filed September 9, 1918. Serial No. 253,230.

To all whom it may concern:

Be it known that I, HENRY POPE, a citizen of the United States, residing at Chicago, county of Cook, State of Illinois, have invented an Improvement in Reusable Knitted Gauze Surgical Dressings, of which the following description, in connection with the accompanying drawing, is a specification, like characters on the drawing representing like parts.

The object of this invention is to provide a surgical dressing for use in the treatment of wounds which shall be adapted to be inserted in or applied to the wound which shall secure minimum irritation to mucous and serous surfaces when brought into contact therewith, which shall be cheaply and expeditiously manufactured, which shall insure that yarn ends or fibers shall not remain adhering to the wound or the said surfaces after removal of the dressing, and which may be readily washed and cleansed, restored to its original shape, and re-used until worn out.

These objects of the invention are secured by forming from soft absorbent cotton yarn a loosely knitted tubular gauze fabric of the required size, length and shape, by securing the edges at the end portions of the tubular sections with an elastic fastening of cotton yarn to prevent fraying or raveling and by thus producing a dressing which may be readily washed and cleansed, restored to its original shape and re-used until worn out.

These and other objects of the invention will appear more fully from the accompanying description and drawings and will be particularly pointed out in the claim.

The drawings illustrate a few of the principal forms of re-usable knitted gauze surgical dressings embodying the invention.

In the drawings,

Figure 1 is a perspective view of an abdominal roll embodying the invention;

Fig. 2 is a view of a mouth mask;

Fig. 3 is a view of a square dressing pad formed and folded to present eight thicknesses of the knitted gauze;

Fig. 4 is a view of a small sponge;

Fig. 5 is a much enlarged detail of a section of rib knitted fabric showing the preferable formation of the knitted gauze.

Fig. 6 is an enlarged detail showing one form of elastic finish for securing the end

edges of the tubular knitted gauze.

The invention is adapted to be embodied

in any of the various forms of surgical dressings which are to be inserted in or brought into contact with a wound or exposed mucous or serous surfaces. Such dressings are generally known as gauze packings, sponges, compresses, dressing pads, absorbent pads, abdominal rolls, head nets, head and face masks, mouth masks, etc., and, as the general shape, form and size of such dressings are well known, only a few of the principal types are illustrated in the drawings.

These surgical dressings have almost uniformly been made heretofore of a very light weight woven fabric known as "gauze" and this fabric by reason of the fact that it is woven in a loom is composed of hard twisted fine yarn. The absorbent character of this fabric largely depends upon the interstices of the fabric because the hard twisted character of the yarn materially restricts the absorbent character of the yarn itself. This fabric is of a thin and unstable nature and is folded up into a number of thicknesses and great care has to be exercised to fold in and protect the raw edges to minimize the constant danger from the yarn or threads of which it is composed becoming loosened at the edges and adhering to and remaining in the wound after the dressing has been removed therefrom. Owing to the light weight of this fabric it is impractical to finish the edges to prevent the yarn or thread from becoming loosened therefrom, and owing to the character of the fabric it is so impractical to cleanse such dressings and restore the fabric to condition fit for re-use that it is almost the universal practice to throw such dressings away after a single service. An enormous amount of labor, usually by the hands of volunteer workers, is required to make up surgical dressings from this woven fabric and enormous quantities of the fabric are consumed.

In the present invention the material from which the surgical dressings are made is formed from soft absorbent cotton yarn which has by reason of its soft character large absorbent characteristics. This soft absorbent cotton yarn is loosely knitted into a tubular gauze fabric of such size that when the tubular fabric is flattened out it presents the width required for the particular dressing. This soft knitted fabric is preferably formed on the usual circular rib knitting machine, the character of rib knitted work which is well known in the knitting

art being illustrated in Fig. 5. This knitted fabric is readily produced on the rib knitting machine which is capable of handling soft yarn at a high rate of speed and thus in 5 a most cheap and expeditious manner. By reason of its essential formation in tubular form there are no side edges from which fibers or threads may become detached or loosened. The entire fabric is absorbent both 10 with respect to the yarn itself and the interstices of the fabric and is of a soft non-irritating character.

The fabric is preferably knit continuously and severed into sections of the length required. 15

The end edges are finished with an elastic fastening of cotton yarn. This elastic fastening may be effected either by a separate operation after the completion of the knit 20 tubular sections or it may be effected in the operation of knitting itself. In the latter case the cotton yarn of the tubular knit section is formed into an elastic fastening by the knitting of an ordinary welt or a French 25 welt or any similar well known concatenation which provides a non-raveling finish. Such an elastic fastening effected in the knitting process can usually be provided at only one end of the tubular knit section. 30 Preferably, therefore, the elastic fastening is provided at one or both ends of the tubular section by a subsequent operation. For this purpose any well known trimming and overseaming machine such as the well known 35 Merrow, Union Special, Wilcox and Borton or similar machines may be employed. Such machines trim and cover over and bind the edges, securely fastening the yarn ends and preventing danger of the yarn ends fraying 40 or raveling out, at the same time producing a fastening of a highly elastic nature.

In making up the dressing a tubular section of a single thickness of knitted web may be employed, as in most of the dressings 45 illustrated, or two or more sections of the tubular fabric may be concentrically superposed as in the case of the large pad illustrated in Fig. 3 where two such concentrically superposed tubular sections 2 and 3 are 50 employed. In such cases the superimposed edges are secured by a single elastic fastening 4 as shown in the said Fig. 3.

The tubular section of knitted gauze may be folded on itself one or more times to form 55 the required thickness as for example in the case of the large pad illustrated in Fig. 3 wherein the two ply tubular section is shown doubled thus producing eight thicknesses.

The dressings may be provided when required with tapes 5 for securing the dressings in place or for removing the dressings from the wound, such tapes being illustrated in several of the figures of the drawings.

It will thus be seen that all danger of 60 yarn or fibers becoming separated from the

dressing and adhering to or remaining in the wound after the removal of the dressing therefrom is prevented because there are no side edges of the dressing by reason of its tubular formation and because the end edges 70 are protected by the elastic fastening.

The elastic fastening, when of the type illustrated, is effected expeditiously and cheaply by means of well known types of trimming and overseaming machines and 75 when of the welt type is effected in the knitting operation itself, so that the entire operation of making the fabric of the dressing ready for folding into the required number of thicknesses is performed by machinery. 80

The dressing thus formed, whatever may be its shape, size and number of thicknesses, is of a soft and highly absorbent character and produces a minimum amount of irritation when brought into contact with or 85 placed in a wound or brought into contact with mucous or serous surfaces.

After such a dressing has once been used and has become impregnated with pus or blood from the wound it may be readily and 90 easily cleansed, washed, sterilized, restored to its original condition and re-used. Any suitable process or processes may be employed for this purpose. Preferably such dressings after use are soaked in cold water 95 with frequent rinsings from 12 to 24 hours, are then boiled for 20 to 30 minutes, are then washed with soap and hot water in a washing machine, are then thoroughly rinsed and passed through a wringer, and are then 100 dried.

Preferably the drying operation may be performed by slipping the tubular fabric of the dressing over a steam heated metallic form. The dressing is thus dried and left 105 in its original size and shape. The tubular knitted gauze is then in its original condition and is then sent to the operating pavilion where the nurses fold it up into the required number of thicknesses, pack the dressings in bundles and sterilize them in the autoclave. But any suitable method may be employed for washing, cleansing, sterilizing and drying the dressings. 110

The principal point is that the dressings 115 of this invention are capable of thus being washed, cleaned and sterilized and restored to their original condition. They come out of these operations soft and pliable and ready for re-use and this re-use of the dressings may be repeated until the fabric is worn out. The life of the dressings and the number of services or re-uses thus depends chiefly upon the wear due to the washing and cleansing operation.

The dressings of this invention may be manufactured at substantially the cost, or even less than the cost, of dressings made from woven gauze and as these dressings are capable of being re-used a large number of 120 125 130

times the actual cost of the dressings per application or service is reduced to a very small figure.

By reason of the elastic character of the tubular knitted gauze fabric forming the dressing, pads of absorbent material of any suitable character may be inserted in the tubular fabric when required and may readily be removed therefrom after use.

10 Having fully described my invention, what I claim as new and desire to secure by Letters Patent is:

A re-usable knitted gauze surgical dressing composed of soft absorbent cotton yarn

loosely knitted into a section of tubular form 15 and having the end edges of the tubular section secured against fraying or raveling by an elastic fastening of cotton yarn, the said dressing being insertible in or applicatory to a wound or applicatory to mucous or serous 20 surfaces without danger of yarn ends remaining in the wound or upon said surfaces after removal of the dressing, and the said dressing being washable and cleansable and re-usable until worn out.

25 In testimony whereof, I have signed my name to this specification.

HENRY POPE.
